UNITED STATES PATENT OFFICE.

GEORGE ROBINSON GOSSLING, OF WALTON-ON-THAMES, ENGLAND,
ASSIGNOR TO CLAUDIUS ASH & SONS, LIMITED, OF LONDON,
ENGLAND, A CORPORATION OF GREAT BRITAIN.

HANDPIECE FOR DENTAL ENGINES.

SPECIFICATION forming part of Letters Patent No. 794,007, dated July 4, 1905.

Application filed November 8, 1904. Serial No. 231,859.

To all whom it may concern:

Be it known that I, GEORGE ROBINSON GOSSLING, a subject of the King of Great Britain, residing at Walton-on-Thames, county of Surrey, England, have invented a certain new and useful Handpiece for Dental Engines, of which the following is a specification.

The invention relates to handpieces for dental engines; and it consists of an improved form of construction of certain of the parts of a handpiece, for which I have filed an application for Letters Patent of the United States on the 5th day of April, 1904, under Serial No. 201,673, the object being to avoid the necessity of using a screw-driver in attaching the casing to the handle, thus enabling the parts to be more readily separated for cleaning and sterilizing.

In the accompanying drawings, Figure 1 is a side elevation, partly in section, of the handpiece with my present improvement applied thereto. Fig. 2 is a rear elevation of same with one of the locking-plates turned to one side. Figs. 3 and 4 are also rear elevations showing the two parts, as in Fig. 2, separated, but with both locking-plates removed. Fig. 5 is a rear elevation of the two locking-plates at an angular position to one another; and Fig. 6 is a side elevation of Fig. 5.

As stated, the present invention comprises an improved means for attaching the casing *a* to the holder *d*, and in carrying out the same the casing *a* is provided with a solid lug *b*', in which is formed the slot or recess *b*'' for the end *l*' of the detachable outer locking-plate *l* to engage in after the projection *o* of the detachable inner locking-plate *n* has been engaged in the recess *a*'', Fig. 3, of such head. These two plates are pivotally connected by a stud *m*, and the plate *l* carries the flat-faced pin *p*, which is adapted to pass through a hole in the plate *n* and engage the flat face of the shank of the usual tool *i* to lock it in the socket *e*. The stud *m*, however, connecting such plates *l* *n*, is prolonged on the inside, Figs. 1 and 6, as at *m*', and a hole *m*'' is formed in the groove *a*'' of the casing *a*, so that it may pass therethrough and into a hole

m''', Fig. 4, in the extended tubular portion *d*' of the handle *d*, which carries the casing, so that the pin *m*' will lock the casing both from a rotary movement or one of withdrawal when the plates *n* *l* are in position. To insure the holes *m*'' *m*''' being brought quickly together, a pin *v*, projecting from the handle *d* by the side of the part *d*', is adapted to engage a recess *v*' in the lug *b*' of the casing *a*. The walls of the portion *d*' of the handle are preferably made thick enough to form a long bearing for the spindle *t*, and to assist in lubricating this a groove *w*, Figs. 1 and 4, is formed in the part *d*', terminating in a hole *w*', which passes through the wall to the interior, so that oil can be introduced to the spindle *t* and other parts by way of the hole *r* in plate *n* and the hole *r*' in the groove *a*'' of the casing *a*.

It will be seen that the tool may be driven by suitable gears, carried, respectively, by the socket *e* and spindle *t*, and that the section *a* can be readily separated from the handle *d* by withdrawal at any time when the two plates *l* *n* are removed from the casing for the purpose of removal of the tool-socket for cleaning or sterilizing of the parts as they carry with them the connecting-pin *m*'.

I claim as my invention—

1. In a handpiece for dental engines, a handle provided with an extended tubular portion having a transverse hole therein, a tool-holding socket and casing adapted to fit over the tubular portion of the handle and having a hole therein normally registering with the aforesaid hole in the tubular end portion of the handle, plates connected together, the one adapted to engage the casing at one point and the other at another point and means carried thereby and adapted to enter the said holes in the casing and tubular extension of the handle when the plates are in position.

2. In a handpiece for dental engines, a handle provided with an extended tubular portion having a transverse hole therein, a tool-holding socket and casing adapted to fit over the tubular portion of the handle and having a hole therein normally registering with the

aforesaid hole in the tubular end portion of the handle, means insuring the registration of said holes, plates pivotally connected together, the one adapted to engage the casing at one point and the other at another point and means carried thereby and adapted to enter the said holes in the casing and tubular extension of the handle when the plates are in position.

3. In a handpiece for dental engines, a handle provided with an extended tubular portion having a transverse hole therein, a tool-holding socket and casing adapted to fit over the tubular portion of the handle and having a hole therein normally registering with the aforesaid hole in the tubular end portion of

the handle, means insuring the registration of said holes, plates, the one adapted to engage the casing at one point and the other at another point, a stud pivotally connecting said plates together and adapted to enter the said holes in the casing and tubular extension of the handle when the plates are in position. 20

In testimony whereof I have hereunto set my hand in the presence of two subscribing witnesses.

GEORGE ROBINSON GOSSLING.
